UNITED STATES PATENT OFFICE.

WALTER O. REID, OF MINNEAPOLIS, MINNESOTA.

SIDE-TONE ELIMINATOR FOR TELEPHONES.

Application filed October 19, 1925. Serial No. 63,849.

My invention has for its object to provide an extremely simple and highly efficient side tone eliminator for telephones, and to this end it consists of the novel devices 5 and combinations of devices hereinafter described and defined in the claim.

As is well known, local noises entering the mouthpiece of the transmitter of a telephone pass directly through the instrument to the 10 receiver where they are clearly audible to a person using the instrument, thus making it very difficult to hear a person talking at the other end of the line.

The invention, in its preferred form, is 15 in the nature of an attachment for the mouthpiece of the transmitter of a telephone and provides a yieldingly opened valve with a manually operated controller for operating said valve, at will, to close said mouth- 20 piece.

In the accompanying drawings, which illustrate the invention, like characters indicate like parts throughout the several views.

25 Referring to the drawings:

Fig. 1 is a fragmentary view, partly in side elevation and partly in section, of a portable telephone having the invention applied to the mouthpiece of its transmitter;

30 Fig. 2 is a view partly in plan and partly in section, taken on the line 2—2 of Fig. 1, on an enlarged scale; and

Fig. 3 is a view principally in longitudinal central section of the invention re- 35 moved from the telephone with some parts broken away.

Of the parts of the telephone illustrated, it is important to note the stand 4, transmitter 5 and its mouthpiece 6 having in its 40 base 7 a plurality of sound passages 8.

The attachment, as illustrated, includes a normally opened conically formed valve 9, arranged to be pressed onto the base 7 of the mouthpiece 6 to close its sound passages 45 8.

On the face of the valve 9 is a piece of felt 10 or other pliable material arranged for direct contact with the base 7 of the mouthpiece 6 to form a tight joint therewith when said valve is closed. Said valve 50 9 is provided with an axially extended stem 11 mounted in a tubular guide 12 secured to the under side of a holder 13 in the form of a spider, the arms of which span the mouthpiece 6 and rest on the rim thereof.

55 To detachably secure the holder 13 to the mouthpiece 6, the outer end portion of

its arms are bent to form hook-like members 14 arranged to be sprung into interlocking engagement with the rim of said mouthpiece. One of the hook-like members 60 14 is provided with an outturned finger piece 15 by which it can be sprung outward to release the holder 13 from the mouthpiece 6. This same finger piece 15 is also arranged to engage the rim of the mouthpiece 6, after the other two hook-like members 14 have been interlocked therewith, and when pressure is applied thereto will be sprung outward with a cam-action and snapped into interlocking engagement with 70 said rim of the mouthpiece 6.

As one means of manually operating the valve 9, to press the same onto the base 7 and close the mouthpiece 6, one end of an endwise movable flexible cable 16, of twisted wire or the like, is attached to the outer end of the valve stem 11. Attached to the other or outer end of the cable 16 is a stem 17 which forms a rigid extension therefor and has on its outer end a thumbpiece 18 by 80 which the cable 16 may be moved endwise. On the inner end of the stem 17 is a cylindrical body member 19 mounted in a rigid tubular casing 20 for axial sliding movement.

A cap-like holder 21 is secured to the outer end of the casing 20 and is provided with an axial bore through which the stem 17 extends for endwise sliding movement. The inner end of the casing 20 is closed 90 except for a passage for the cable 16. A coiled spring 22 encircling the cable 16 is compressed between the closed inner end of the casing 20 and the body member 19 and normally holds the stem 17 and its thumbpiece 18 projected to hold the valve 9 open by means of the cable 16. In the open position of the valve 9, the same engages the valve stem guide 12 as a stop.

To prevent the cable 16 from buckling 100 when the thumb-piece 18 is depressed to close the valve 9, the same is mounted in a flexible tubing 23, the outer end portion of which surrounds the casing 20 and extends into the capping member of the holder 21. The inner end of the tubing 23 is secured in a cup-like member 24 detachably secured to the holder 13 by means of a stem 25 having internal screw-threaded engagement with the outer end portion of the valve stem guide 12. On the periphery of the member 24 is a knurled annular rib 26

by which the stem 25 may be screwed into or out of the valve stem guide 12.

When a person is talking over a telephone to which the side tone eliminator is applied and where there are side tones interfering with his hearing, he preferably holds the controller for the yieldingly open valve 9 in the same hand in which he is holding the receiver of the instrument, and with the holder 21 between the first and second fingers and with his thumb on the thumbpiece 18.

While a person is talking, the valve 9, of course, is open, but while he is listening he depresses the thumbpiece 18 to close the valve 9 and thereby close the mouthpiece 6 to the transmitter 5 to prevent the side tones from entering the instrument. To open the mouthpiece 6, it is only necessary to release the thumbpiece 18 and thereby permit the spring 22 to open the valve 9.

The above described attachment has, in actual usage, proven highly efficient for the purpose had in view, and can be very quickly snapped onto or off from the mouthpiece of a telephone transmitter.

What I claim is:

A side tone eliminator attachment for telephones having a mouthpiece with a perforated base comprising a spider-like holder applicable to the rim of the mouthpiece and having a valve stem guide, a yieldingly opened valve having a valve stem mounted in said guide, and a manually operated flexible controller attached to the stem of the valve and operative to project the valve onto the base of the mouthpiece for closing said mouthpiece.

In testimony whereof I affix my signature.

WALTER O. REID.
